UNITED STATES PATENT OFFICE

RAY R. HUTCHESON, OF RICHMOND HILL, NEW YORK, ASSIGNOR TO WM. DE MUTH & CO., A CORPORATION OF NEW YORK

DESIGN FOR A LIGHTER

Application filed September 24, 1931. Serial No. 41,203. Term of patent 3½ years.

To all whom it may concern:

Be it known that I, RAY R. HUTCHESON, a citizen of the United States of America, and a resident of Richmond Hill, county of Queens, and State of New York, have invented a new, original, and ornamental Design for Lighters, of which the following is a specification, reference being had to the accompanying drawings, forming a part hereof.

In the drawings:

Fig. 1 is a side elevational view of the lighter.

Fig. 2 is a top plan view of the same, the figure being omitted,

Fig. 3 is a front view of the same, the figure being omitted, the cap or cover over the lighter mechanism being shown in the open position in dotted lines.

The design is characterized by a radiator-like casing about the lighter mechanism, and a figure standing in front of this casing.

I claim:

The ornamental design for a lighter substantially as shown and described.

RAY R. HUTCHESON.
